UNITED STATES PATENT OFFICE.

WARREN T. REASER, OF FAIRMONT, NEBRASKA, ASSIGNOR TO THE ROUND VALVE COMPANY, OF CHICAGO, ILLINOIS.

BALANCED OSCILLATING VALVE.

SPECIFICATION forming part of Letters Patent No. 394,505, dated December 11, 1888.

Application filed December 22, 1887. Serial No. 258,734. (No model.)

To all whom it may concern:

Be it known that I, WARREN T. REASER, a citizen of the United States, residing at Fairmont, in the county of Fillmore and State of Nebraska, have invented certain new and useful Improvements in Balanced Oscillating Valves for Steam-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to balanced oscillating valves for steam-engines, the object being to so construct the valve patented to me May 24, 1887, as to render its application more practical and economical. In this improved valve I place the steam-ports sufficiently above the center of oscillation to counteract the upward pressure of the exhaust-cavity, and also extend the valve-rod through both sides of the outer steam chest or casing, thus obviating any twisting or torsional strains on the valve, which, with its casing, is entirely submerged in live steam, the whole being inclosed in the outer steam-chest, thus preventing unequal expansion and consequent wear.

In the drawings, Figure 1 is a sectional elevation of an engine provided with my improved valve. Fig. 2 is a cross-section through the center of valve on line *x* *x* of Fig. 1. Fig. 3 is an enlarged sectional elevation of the valve on the line *y* *y* of Fig. 2. Fig. 4 is an enlarged cross-section of the valve.

Like letters indicate like parts in the several views.

- A is the cylinder of an engine.
- B is the outer steam-chest.
- C is the balanced valve.
- D is the valve-case.
- a* is the valve-rod. *b* is the exhaust-cavity in the valve.
- c c* are steam-ports cut through the valve sufficiently above its center to provide for its being always held down on the cylinder steam-ports *d d*. *k k* are strengthening-bars

crossing the steam-ports in the valve. *e* is a crank-arm attached to the valve-rod *a*, for the purpose of attaching the eccentric-rod of the engine, which gives motion to the valve. This arm may be attached to one side of the steam-chest, as shown in enlarged valve, Fig. 3, or to both sides, as shown in Fig. 2, so that connections may be made at both ends and equalize the strain.

fffff are spiral springs for pressing the packing-rings against the casing D, and are placed in recesses in the flange.

h is the exhaust-port connecting with the eduction-pipe *j*.

In constructing an engine to be operated with this valve I prefer to cast the side walls of the steam-chest B integral with the cylinder, the cover being removable and secured to the side walls of the chest by bolts in the ordinary manner. Within this chest and firmly bolted to the cylinder is the cap D, semicircular in cross-section and of such length and diameter as to inclose the upper half of the valve C. The lower half of the valve occupies a semicircular recess formed in the cylinder. Said valve also has a cavity, *b*, in its lower side, which cavity receives the exhaust-steam coming from each end of the cylinder through the passages *d d*, and opens into the exhaust-passage through the port *h*. It will thus be seen that one half of the valve C is within the recess of the cylinder, the other half being covered by the cap D. This cap, as well as the valve, is open at both ends, thus giving free entrance for steam from the steam-chest to the interior of the valve, whence it passes through the ports *c c* and *d d* alternately to opposite ends of the cylinder as the valve is oscillated, and, after its work in said cylinder is done, escapes through the port *b* into the exhaust-passage. The valve-seat, forming an integral part of the cylinder in the steam-chest, extends upward into said chest, so that the steam passes down at each end of the valve to within a short distance of the bore of the cylinder, thus keeping the valve-seat and the case D at the same temperature, as well as allowing a free entrance at both ends of the valve. To prevent leakage of steam through between the ends of the valve

and the valve-seat, each end of the valve is provided with a radially-projecting flange, in which is formed a circular groove containing suitable packing-rings that are retained 5 in contact with the ends of the case and the sides of the valve-case by the coil-springs *f*, placed in recesses of the groove behind the packing-rings. As in a valve with long steam-ports there would be a liability to spring in 10 the opposite walls of said ports, the strengthening bars or bridges *k* are cast integral with the valve, and are placed along the ports at such distances from each other as to give the needed stiffness to the valve. The rod or 15 axle *a* passes through the center of the valve, and has its bearings in the sides of the steam-chest, its ends projecting therefrom and one or both provided with crank-arms, to which the rod from the eccentric of the engine is attached to give motion to the valve.

The operation of these devices will be readily understood from the above description in connection with the drawings.

Steam enters the chest through the inlet *p*, 25 having free access to the interior of the valve through its ends, and thence passes through the ports as the valve is oscillated alternately to the opposite ends of the cylinder.

Having thus described my invention, I 30 claim as new, and desire to secure by Letters Patent, the following:

1. In balanced oscillating valves for steam-

engines, the cap *D*, inclosing the upper half of the valve *C*, in combination with said valve, the cylinder inclosing the lower half, and the 35 whole being surrounded by the steam-chest *B*, its sides made integral with the cylinder, all the parts being arranged, as shown and described, to admit live steam to both ends of the valve, as specified.

2. In a balanced oscillating valve for steam-engines, the combination of the valve *C*, having ports *c c* above the center of oscillation, the cap *D*, inclosing the upper half and the cylinder *A* the lower half of said valve, the 45 packing-rings, and springs in a recess at each end of the same, the steam-chest *B*, its sides made integral with the cylinder, the valve rod or shaft *a*, and the crank-arms *e*, attached to each end thereof, in the manner shown and 50 described, and for the purpose set forth.

3. In a balanced oscillating valve for steam-engines, the valve *C*, open at both ends and provided with radially-projecting flanges and packing-rings therein, also with ports *c c*, extending nearly the whole length of the valve, and bars *k k*, bridging said ports, in the manner specified, and for the purpose set forth.

In testimony whereof I affix my signature in presence of two witnesses.

WARREN T. REASER.
